INVENTOR

David Michie

UNITED STATES PATENT OFFICE.

DAVID MICHIE, OF IRWIN, PENNSYLVANIA.

ELECTRIC IRON.

Application filed December 15, 1922. Serial No. 607,206.

To all whom it may concern:

Be it known that I, DAVID MICHIE, a citizen of the United States, and a resident of Irwin, in the county of Westmoreland and State of Pennsylvania, have invented a new and useful Improvement in Electric Irons, of which the following is a specification.

My invention relates to electrically heated appliances and particularly to electric flat irons.

The object of my invention is to provide a relatively simple and inexpensive construction for an electric flat iron.

In practicing my invention I provide a body portion comprising a sole plate, a top plate, and an electric heating element clamped therebetween, and a cover member therefor. A handle strap is secured to said cover and carries a handle at its upper end. The top plate has an end recess at its rear edge to provide space for a pair of contact terminals of L-shape mounted on a bar of insulating material whose ends are secured against the upper surface of the top plate.

A supply circuit conductor extends through an opening in said cover and has its ends secured to said contact terminals. A helically-wound spring has one of its ends extending through the opening in said cover and is held therein, and surrounds and supports said conductor over a portion of its length. A spring-supporting means comprises a punched and formed sheet metal member which is supported at two points by the handle strap and which, in turn, supports the spring at one point intermediate its ends. The spring-supporting means has an integral portion extending along the rear of the iron, which portion is so formed as to provide, in combination with the upper part thereof, a three-point support for the iron in a backwardly-tilted position.

In the single sheet of drawings, Figure 1 is a view, in side elevation, of an electric iron embodying my invention, certain parts being cut away;

Fig. 2 is a view, in rear elevation, of a body portion of an electric iron and an iron-supporting member embodying my invention;

Fig. 3 is a fragmentary top plan view of a body portion;

Fig. 4 is a partial view, in rear elevation,

of an electric iron with the rear wall of the cover removed, and

Fig. 5 is a top plan view of a sheet metal member for supporting the conductor supporting means and also the iron, shown in an extended position.

An electric iron 11 comprises a bottom or sole plate 12, a top plate 13, and a relatively thin flat electric heating element 14 located therebetween. The sole plate, top plate, and the heating element comprise what may be termed the body portion of the iron. The sole plate 12 is provided with a depression 15 in its upper surface within which the heating element 14 and the bottom portion of the top plate 13 are located, this construction being adopted in order that a close operative engagement may be effected between the three members constituting the body portion, and also to locate the heating element as closely as possible to the working surface of the sole plate 12. The top plate is clamped against the heating element and the sole plate by a plurality of machine screws 16 which extend through openings 17 in the top plate 13, one of the openings 17 being located near the front of the iron, and two of the openings 17 being located at the sides of the rear portion of the iron.

The iron 11 is substantially of triangular contour and the side edges of the sole plate are provided with a relatively long beveled surface, as may be noted more particularly in Fig. 2 of the drawing.

A cover member 18, of stamped sheet metal, is provided at the top of the body portion of the iron. A handle member for the iron comprises a handle strap 19, the intermediate portion of which is secured against the top of the cover member 18 by a rivet 21. A handle 22, of a suitable heat-insulating material, is supported by the two ends of the handle strap 19 by a bolt 23 extending therethrough and having a nut 24 at one end to tightly clamp the handle between the ends of the handle strap. The handle strap 19 is further secured against the cover 18, and the cover 18 is secured to the body portion of the iron, by two machine screws 25 extending through the handle strap and the cover member and having screw threaded engagement with two upstanding, integral lugs 26 located on the upper surface of the top plate. The top

plate 13 is further provided on its upper surface with a web 27 which extends longitudinally between the two lugs 26, in order that the top plate may have sufficient stiffness.

The top plate has an end recess 28 adjacent the rear edge thereof in order to provide space for a terminal device for the body portion of the iron. A bar 29 of a suitable electric-insulating material extends across the top of the end recess 28 and has its ends secured to the upper surface of the top plate by machine screws 31. The bar 29 carries a pair of spaced contact terminals 32, of substantially L-shape, the horizontally-extending portion of each of which is secured to the bar by suitable means such as a rivet 33. If necessary the bar 29 may be provided with a pair of spaced slots or recesses in its vertical rear face to receive the vertically-extending portion of the members of L-shape, whereby an accidental engagement of the same is effectively prevented. The ends of the resistor wire comprising a part of the heating element 14 are connected to the contact terminals 32 by means of screws 34.

As the heating element 14 forms no part of my invention it is not illustrated in detail and may be of any type usually employed in the art. It is here illustrated generally as comprising two layers of electric insulating material, between which is located a resistor member.

The cover member 18 is provided at its rear end with an opening 35 through which the ends of a supply circuit conductor 36, comprising the usual twin wires may extend, the ends of the twin conductors being connected respectively to the several terminal members 32 by machine screws 37. An open helically-wound spring 38 surrounds and supports the conductor 36 over a portion of its length immediately adjacent the iron. The spring 38 is provided, at its inner end, with a turn of larger diameter than the others in order that it may extend through the opening 35 in the cover member and be held therein to prevent its disengagement from the cover member. If necessary or desirable, a button of suitable insulating material (not shown) may be provided at the outer end of the spring 38 to present a finished appearance.

A means for supporting the helical spring 38 and for supporting the iron in a backwardly-tilted position comprises a sheet metal member 39 which has an upper end portion 41, two laterally-projecting portions 42 intermediate its ends, and a lower end portion 43 of substantially U-shape. The portion 41 is provided with an opening 44 therethrough, the metal immediately adjacent the opening being embossed to provide a relatively long bearing surface for

engaging and supporting the helical spring member 38. The portion 41 is further provided with a small integral extension 45 which is adapted to extend through an opening in the rear portion of the handle strap 19 and be bent over thereagainst in order to support the upper part of the member 39 from the handle strap. The two intermediate portions 42 are bent to substantially arcuate form and the end portions thereof, which are of reduced width, extend through a suitable opening in the rear part of the handle strap 19 immediately above the cover member 18. The width of the opening in the handle strap is substantially equal in width to double the thickness of each of the portions 42. The ends of the portions 42 extending through the handle strap are bent over in substantially the same manner as hereinbefore described for the portion 45 in order to securely clamp these portions against the handle strap 19 and to thereby support the intermediate portion of the member 39 from the handle strap 19. The portion 43, of U-shape, is bent at an angle relatively to the portion 41 so that it may extend parallel to the rear edge surface of the cover member 18. The outer ends of the portions of U-shape are bent at substantially right angles to the inner portion and are then return-bent, substantially as illustrated in Fig. 1 of the drawing.

The hereinbefore described construction of the sheet metal member 39 provides a means for supporting the iron in a backwardly-tilted position, the iron resting upon the projecting parts of the return-bent portions of the portion 43, and upon the part 41 immediately adjacent the bend thereof. The member 39 provides a means for supporting the conductor-supporting means in its proper operative position relatively to the iron, and is itself secured only to the handle strap so as to be removable from the body portion of the iron with the handle strap. Any desired marking may also be applied to the outer surface of the member 39 at any desirable location thereon.

To assemble the iron the body portion, comprising the sole plate, top plate and heating element are assembled, and the bar supporting the contact terminals is secured thereon. The handle, handle strap, cover member, spring and spring-supporting member are also assembled in proper operative positions relatively to each other. The conductor cord is then threaded through the spring and the ends thereof secured to the contact terminals. The cover member is then placed in its proper operative position on the body portion, the cord being drawn through the spring as required.

To disassemble the iron, it is only necessary to remove the screws 25, after which

the cover member, handle strap and handle, the sheet metal member 39 and the helical spring 38 may be moved away from the body portion of the iron, the spring moving 5 along over the conductor 36 until the operator can release the screws 37 to permit of removing the ends of the twin leads from engagement with the contact terminals. The body portion of the iron may now be disassembled, without interference from the other parts of the iron.

Various modifications may be made in the device embodying my invention without departing from the spirit and scope thereof, 15 and I desire that only such limitations shall be placed thereon as are imposed by the prior art or are specifically set forth in the appended claims.

I claim as my invention:

20 1. In an iron, in combination, a body portion, a cover, a handle strap secured to said cover, and a three-point supporting member for said iron secured to said handle strap only by integral portions extending 25 therethrough and bent thereover.

2. In an iron, in combination, a body portion, a cover, a handle strap secured to said cover, and means for supporting said iron on three points at the rear end thereof, said 30 means comprising a single formed piece of sheet metal having integral portions extending through and bent over against said handle strap.

3. In an electric iron, in combination, a body portion, a cover therefor, a handle strap secured to said cover, and means permanently secured only to and supported by said handle strap for holding a conductor-supporting member, and for supporting the 40 iron in an inoperative position.

4. In an electric iron, in combination, a body portion comprising a heating element, a cover therefor, a handle strap secured to said cover, supply-circuit conductors connected to said heating element, a resilient conductor-supporting means, and a single means secured only to said handle strap for holding said conductor-supporting means in its proper operative position relatively to 50 said iron, and for supporting said iron in an inoperative position.

5. In an electric iron, in combination, a body portion comprising a heating element, a cover therefor, a handle strap secured to said cover, supply-circuit conductors connected to said heating element, a resilient conductor-supporting means, and means comprising a single stamped and formed sheet metal member having integral means 60 for securing it to said handle strap only, for holding said conductor-supporting means in its proper operative position relatively to said iron.

6. In an electric iron, in combination, a body portion comprising a heating element,

a cover therefor, a handle strap secured to said cover, supply-circuit conductors connected to said heating element, a resilient conductor-supporting means, and means comprising a single stamped and formed 70 sheet metal member having integral means for securing it to said handle strap only, for holding said conductor-supporting means in its proper operative position relatively to said iron and for supporting said iron in a 75 backwardly-tilted position.

7. In an electric iron, in combination, a body portion comprising a heating element, a cover, a handle strap secured to said cover, a supply-circuit conductor permanently connected to said heating element, a resilient means for supporting said conductor over a portion of its length, and means permanently secured to said handle strap only for holding said resilient conductor-supporting 85 means at one point intermediate its ends, and for providing a three-point support for holding said iron in a backwardly-tilted position.

8. In an electric iron, in combination, a body portion comprising a heating element, a cover, a handle strap secured to said cover, a supply-circuit conductor permanently connected to said heating element, an open helically-wound spring surrounding and 95 supporting said conductor over a portion of its length, and means permanently secured to said handle strap only for holding said spring at one point intermediate its ends, and for providing a three-point support for 100 said iron when in a backwardly-tilted position.

9. In an electric iron, in combination, a sole plate, a top plate having an end recess at its rear edge, a heating element located 105 between said plates, a bar of electric-insulating material supported by said top plate above said end recess, a pair of contact terminals, of L-shape, secured to said bar, a supply-circuit conductor, and means for 110 electrically connecting said supply-circuit conductor and said heating element to said terminals of L-shape.

10. In an electric iron, in combination, a sole plate, a top plate having an end recess 115 at its rear edge, a heating element located between said plates, a bar of electric-insulating material supported by said top plate above said end recess, a pair of contact terminals, of L-shape, secured to said bar, a 120 cover member having an opening therethrough adjacent the rear portion thereof, a supply-circuit conductor extending through said opening in said cover member and electrically connected to said terminals of L-shape, a resilient conductor-supporting and protecting member having one end extending into said opening in said cover member and surrounding said conductor over a portion of its length. 125 130

11. In an electric iron, in combination, a sole plate, a top plate having an end recess at its rear edge, a heating element located between said plates, a bar of electric-insulating material supported by said top plate above said end recess, a pair of contact terminals, of L-shape, secured to said bar, a cover member having an opening adjacent the rear portion thereof, a handle member secured to said cover, a supply-circuit conductor extending through said opening in said cover member and electrically connected to said contact terminals of L-shape, an open helical spring having its lower end extending into the opening in said cover and held therein and surrounding said conductor over a portion of its length, and a combined spring-holder and iron-supporting means operatively secured to said iron.
12. In an electric iron, in combination, a sole plate, a top plate having an end recess at its rear edge, a heating element located

between said plates, a bar of electric-insulating material supported by said top plate above said end recess, a pair of contact terminals, of L-shape, secured to said bar, a cover member having an opening adjacent the rear portion thereof, a handle member secured to said cover, a supply-circuit conductor extending through said opening in said cover member, and electrically connected to said terminals of L-shape, an open helical spring having its lower end extending into the opening in said cover and held therein and surrounding said conductor over a portion of its length, and a combined spring-holder and iron-supporting means secured only to said handle member.

In testimony whereof, I have hereunto 40
subscribed my name this 9 day of Decem-
ber, 1922.

DAVID MICHIE.
